(57) **CLAIM**

The ornamental design for a bit for a ground engaging machine implement, as shown and described.

DESCRIPTION

FIG. 1 is a front, left perspective view of a bit for a ground engaging machine implement showing our new design;

FIG. 2 is a rear, left perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

(Continued)

The broken lines illustrate structure or features which form no part of the claimed design.

1 Claim, 4 Drawing Sheets
